Application February 11, 1943, Serial No. 475,499

26 Claims. (Cl. 197—20)

This invention relates in general to devices for controlling printing mechanism by a record and more specifically to mechanism for controlling the operation of a typewriter by a tape perforated in a stenographic machine.

An object of the invention is the provision of an improved and rapidly operated record controlled typewriter. The controls include electrical devices making it possible to record a short word or a portion of a long word for each cycle of operation of the machine.

Another object of the invention is the provision of devices for sensing a tape, perforated under control of a stenographic machine, wherein the perforation representations of a plurality of characters are punched in each control area of the tape. The sensing devices are made effective successively in a left to right sequence across the tape, so that the type are operated progressively to record initial consonants, intermediate vowels and final consonants in the order mentioned. Special control perforations are sensed at the left and right of the character perforations to initiate typewriter controls for tabulation, line space or capitalization before character printing, and spacing control after character printing.

A feature of the invention is the provision of character counting devices for fitting the last word of a line within a predetermined length of line. When the typewriter carriage approaches within the range of the last twenty character spaces of a predetermined length of line, the characters of each succeeding word are measured or counted and compared with the space remaining in the line. If the word or word part is short enough, it is printed. If not, a carriage return operation is automatically initiated, the record sheet is line spaced, and the word is printed at the beginning of a new line.

Should the perforations relating to one word occupy more than one control area on the record tape, a plurality of such areas are analyzed in succession and the character representations therein counted until a space perforation is sensed, denoting the end of the word. The character counting devices are released under control of the sensing device cooperating with the space perforation. Upon release, the counting mechanism is restored in readiness for another character counting excursion whenever the work sheet holder or carriage is within a predetermined range near the end of each line.

Another object of the invention is the provision of automatic carriage return and line spac-

ing devices under control of character counting and word fitting devices.

Another object of the invention is the provision of means for interpreting multiple perforations representative of single characters. The vowels *i* and *u* are each represented by two of three possible vowel representing perforations. The other more frequently occurring vowels, *a*, *e* and *o* are represented by single perforations.

Another object of the invention is the provision of automatic shifting devices operated in connection with selection of special characters. The sensing device of the shift mechanism is associated with the sensing devices of all special characters so that, when a perforation is detected relating to a special character, the shift mechanism is operated prior to the operation of a related character type bar.

Another object of the invention is the provision of shift maintaining means to make possible the printing of titles or headings in capitals. Special "capital start" and "capital stop" perforations are sensed to control the shift lock key and the shift key, respectively, to hold and release the shift mechanism whenever desired.

Another object of the invention is the provision of "error start" and "error stop" devices for eliminating recording while selected portions of the tape are passing under the sensing devices. When the operator of the stenographic punch machine desires to make a correction to eliminate parts of the stenographic work, she operates keys to punch "error start" and "error stop" perforations in the tape, and it is between those two indicia that the special devices of the invention are made effective to eliminate printing.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a front elevation showing the typing machine mounted on a cabinet containing the tape sensing devices.

Fig. 2 shows a portion of the perforated tape. In this form of record all the characters are pre-printed above the related perforation positions.

Fig. 3 shows another form of perforated tape wherein the identifications of the perforations are not preprinted but impressed selectively at the same time that the perforations are punched.

Fig. 4 is a diagrammatic showing of the arrangement of character perforation positions and

the control perforation positions with their related identifications.

Fig. 5 is a sectional elevation view showing the typing and carriage control mechanism of a power driven typewriter.

Fig. 6 is a detail elevation view showing the shift and shift lock keys connected for solenoid operation.

Fig. 7 is a plan view of the typewriter carriage showing the character counting devices and the associated releasing mechanism.

Fig. 7a is a sectional detail view of the counting rack as seen along line 7a-7a in Fig. 7.

Fig. 8 is a plan view showing the plurality of tabulating controls associated with the typewriter carriage.

Fig. 9 is a plan view of the tape sensing devices showing the driving connections.

Fig. 10 is a sectional elevation view of the tape sensing devices.

Fig. 11 is an elevation view of one end of the tape sensing unit showing the clutch mechanisms for controlling the tape counting feed and tape recording feed.

Fig. 12 is a detail view showing the shape of the contact bar underlying the character counting brushes.

Figs. 13a and 13b comprise a wiring diagram of the electrical controls in the machine.

The invention is illustrated in connection with a power driven typewriter known as the "Electromatic" and also identified as the "International." In this machine, the keys merely trip connections to print levers which are then operated by a power driven roller. In the present instance, tripping is performed by impulses derived from a perforated tape made in a stenographic machine wherein the key arrangement is productive of more rapid operation than the usual typewriter, because entire words or substantial parts of long words are recorded in a single stroke or depression of the hands. Before describing the tape and the sensing devices cooperating therewith, it is believed well to point out the mechanical construction of the printing machine which is to be operated under control of the tape.

Referring to Fig. 5, it is noted that the type operating mechanism is of the form disclosed in the Lemmon Patent 2,066,786, issued January 5, 1937. Briefly, the machine comprises a frame 1, in which the type segment 2 is mounted. Type bars 3 are pivotally mounted upon a wire 4 that passes through the segment 2.

The keys 5 are carried by key levers 6 which are pivoted upon a rod 1. Some of the key levers have tails 8 which extend downward to the rear of a continuously running roller 9, and the other key levers have tails 10 which extend downward in front of the continuously running roller 9. The tails 8 and 10 are bifurcated and embrace, respectively, pins 11 and 12 carried by bell cranks 13 and 14. The bell cranks 13 and 14 are pivoted at 15 and 16 upon other bell cranks 17 and 18. The bell cranks 17 and 18 are pivoted at 19 and 20 and carry, at the lower ends thereof, rotary cams 21 and 22. The bell crank 13 is provided at the lower end with a lip 23 which normally stands in the position illustrated in Fig. 1, wherein it obstructs one of two pins 24 carried by the cam 21, and thus prevents rotation of the cam. When a key lever 6 is depressed for rocking one of the tails 8 rearward, the associated bell crank 13 is rocked counterclockwise to move the lip 23 clear of the pin 24. The cam 21 then rocks

clockwise into engagement with the roller 9, which roller is continuously rotated in a counterclockwise direction. As soon as the lip 23 is moved to a non-obstructing position, the roller 9 becomes effective to rotate the cam 21 through a half revolution. By the time that the cam has turned through a half revolution, the lip 23 has been returned to the home position to intercept the other pin 24 on the cam and so arrest rotation of the cam. The rotation of the cam, however, serves to rock the bell crank 17 in a clockwise direction. The bell crank is thus caused to pull downward upon a link 25. This rocks another bell crank 26 in a clockwise direction, causing it to act through a link 27 to pull forward upon another bell crank 28. The bell crank 28 is connected to the tail of the type bar 3 and serves to operate it to print. The motion of the bell crank 28 is controlled in part by a link 29 which is pivoted to bell crank 28 and to the fixed center 37. A contractile spring 38 connected to the bell crank 28 tends to restore the parts to the positions in which they are shown in Fig. 5.

The tails 10 which are carried by other key levers act in a similar manner on cranks 14 to withdraw a lip 31 from obstructing relation to pins 32 provided on the cam 22. This results in actuation of a bell crank 18 and link 33 and operation of the appropriate type bar in the manner already described.

The platen 38 is mounted between a pair of carriage side frames 41 and 42, the lower part of which is connected by a cross bar 43 formed with channels as part of the recess for ball bearings 35 guiding the carriage between fixed cross bars 44 and 45 forming the outer recess of the carriage guide. Attached beneath the cross bar 43 is an escapement rack 46 with which a pair of escapement pawls 47 and 48 cooperate. These pawls 40 are controlled by an escapement lever 49 connected by a link 50 to an operating slide 51 having a cross member 52 extending in the path of all the type bars. When any of the type bars are thrown against the platen to effect an impression, the escapement mechanism is operated to allow movement of the carriage and record sheet held thereon in the usual manner. The details of the escapement mechanism are set forth in the Thompson Patent 1,994,544.

50. The machine is provided with a plurality of tabulating stops for positioning the carriage in three places other than the usual starting position. The tabulating stops are electrically selected under control of the tape so that the record sheet can be positioned to start a paragraph, type a closing line, and put a title under a signature.

Referring to Fig. 5, it is noted that a bar 61 is attached between the carriage side frames. 60 Carried on the bar 61 (Fig. 8) is an adjustable tabular stop 62. Cooperating with the stop are a number of armature detents 63, 64 and 65 operated by magnets identified as TAB #1, TAB #2, and TAB #3, respectively. These magnets are 65 held on the machine by brackets 66 fastened to a vertical frame member 67 (Fig. 5) which is secured to the rear wall 68 of the typewriter. Other U-shaped brackets 69 are attached to member 67 to provide pivots 70 (Fig. 8) upon which the detents 63, 64, 65 are swung in and out of cooperation with the related magnets. Attached to each of the armature detents is a long coil spring 71, pulling slightly to the side of dead center over pivot 70 and normally holding the 70 detents away from the magnets. However, when

any magnet is energized, the associated detent is attracted and rocked in a counterclockwise direction and the end thereof is carried into the path of tabular stop 62. The detent is held in the attracted position because the spring 71 is carried into a position on the side of the dead center 70, opposite to the usual position of the spring. The detent is held in the effective stopping position until it is struck by the stop 62 as the carriage moves into the selected position.

The tabulating operation is initiated in the usual way by automatic or manual operation of the TAB key on the "Electromatic" keyboard along with energization of magnets TAB #1, TAB #2 or TAB #3. This serves to operate a linkage for disengaging the letter space escapement pawls and freeing the carriage for tabulating movement to the left as explained in the Crumrine Patent 1,935,436. Said patent also explains that a tabulating stop lever such as lever 12S (Figs. 5 and 8) is swung in the path of settable tabulating stops to control reengagement of the escapement pawls and stopping of the carriage. This same lever 12S is used in the present case for the same kind of tabulating stop control, but under control of movable stop 62 when cooperating with detents 63, 64 and 65.

In Fig. 8, it is seen that stop 62 is pivotally mounted in any one of the centers 35 in bar 61. The stop is formed with an arm 39 and is rocked counterclockwise by a spring 54. When the stop is struck by one of the detents 63, 64 or 65, said stop is rocked in a clockwise direction and then the detent is restored as the stop continues to move a short distance to the left. Arm 39 cooperates with a parallel linkage comprising a pair of arms 56 pivoted on bar 61 and articulated on the ends of a long link 55 against which the arm bears in all positions.

Also cooperating with link 55 is a bell crank 58 pivoted at 59 (Fig. 5) on a fixed bar 74 in the machine. Extending from the crank are a pair of long pins, pin 72 extends upward against the side of link 55 and pin 73 projects downward against the pointed end of lever 12S. Whenever link 55 is depressed by tabulating stop operation, Fig. 8, pin 72 is also shifted and crank 58 is rocked in a clockwise direction to act on lever 12S through pin 73. As lever 12S is shifted to the left, it operates means for reengaging the letter space escapement pawls 47, 48 (Fig. 5), to hold the carriage in readiness for typing operation as pointed out in Patents 1,935,436 and 2,157,053.

The machine is provided with a shift mechanism for recording capitals and special signs in the manner set forth in the Thompson Patent 1,945,097. The shift and shift lock devices are provided with controls to make them selectively effective under control of the perforated tape.

Referring to Fig. 6, it is noted that the shift key lever 75 has a downwardly extending rod 76 attached to the lever of a plunger inserted in a solenoid 40SH. This last mentioned solenoid is energized to pull down the shift lever whenever capitalization is desired.

Pivoted at 77 on shift lever 75 is a crank 78, the upper end of which carries the shift lock key. The lower end of the crank is formed with a notch 79 designed to cooperate with a downwardly pointing frame bar 80, so that, when the shift lock key is depressed, the shift lever 75 is latched in a lowered position. Automatic operation of the shift lock is made possible by a linkage comprising a rod 81, the upper end of which

is attached to crank 78 in front of the pivot 77. Rod 81 is connected with the plunger of a solenoid 40SL so that, when it is energized, the shift lever 75 is lowered and the crank 78 is rocked in a clockwise direction to latch under member 80. The release of the shift lock is effected by operation of solenoid 40SH to cause a further depression of lever 75 independent of the operation of rod 81 and, when the parts are so operated, a spring 82 pulls crank 78 away from the latching position and allows restoration of the shift lever by spring 80.

Associated with the carriage of the typewriter are devices for detecting when the carriage is located with the printing position near the end of a line, and cooperating therewith are other devices for counting the number of characters in a word about to be printed in the space near the end of said line. Turning to Fig. 7, it is seen that a bar 85 is supported between the carriage side frames 41 and 42. Adjustably secured to said bar is a contact holder 86 formed with a pair of rearward extensions 87 and 88. The extension 87 ends in a vertical web (Fig. 5) to which is attached a bank of four contacts 90, 91, 92, 93 (Fig. 7). The first two contacts 90 and 91 are normally closed and the other contacts 92 and 93 are normally opened. Attached to one blade of the contacts 90 is an extension 94 of insulation material for operating the bank of contacts. Movement of the blades of contacts 90 is communicated to the other three contacts by insulation bars secured to the blades so that operation causes opening of contacts 91 and closure of contacts 92 and 93.

Extending in the path of the insulation operator 94 is a fixed cam 95 formed on the inside of a vertical frame member 96 assembled between the rear frame member 67 and a horizontal plate 40 97 attached to the top of the typewriter frame 68. Since the contact holder 86 (Fig. 7) is adjustably mounted on bar 85, the carriage position at which the stationary cam 95 is struck by insulation bar 94 may be chosen by the operator. For purposes of illustration, it is assumed throughout this specification that the adjustment is made so that justification controls are shifted within twenty character spaces from the end of a line. In other words, when typing is taking place and the carriage is moving toward the left, the contacts remain as shown until there is space remaining for twenty more characters up to the right end of the line. At such a time the insulation extension 94 rides up on the cam face 95 and changes the positions of all four contacts, so that contacts 90 and 91 are opened and contacts 92 and 93 are closed. The operation of these contacts calls into play, letter counting devices described herein-after.

Attached to the other extension 88 projecting from the contact holder 86 (Fig. 7) is another set of contact blades arranged in a vertical direction (Fig. 5) and carrying a normally closed pair of contacts 99. One of the blades carrying contacts 99 is made longer than the other blade and extends below it at 100 in the path of a character or letter space counting slide which is about to be described. When the contacts 99 are operated by cooperation of the character counting slide with the extending contact blade, it is an indication that the word about to be printed is too long for the available space and printing is prevented. Then carriage return and line spacing operations are effected to place the record sheet ready to receive the long word at the beginning of the next line.

The character counting devices are operated by impulses derived from tape sensing commutator devices, which scan one or more perforated areas on the tape to create an impulse for each character perforation sensed. The character counting impulses are directed successively through a counting magnet and continue until a spacing perforation is detected, denoting the end of a word.

In Fig. 7 it is seen that the counting magnet CT 10 is secured to the horizontal plate 97 assembled on the stationary frame at the rear of the typewriter. Fastened to plate 97 is a stud 103 which acts as a pivot for an armature lever 104 associated with counting magnet CT. A spring 105 tends to rock the lever 104 in a clockwise direction against a stop stud 106 also held on plate 97. Pivoted at 107 on the end of armature lever 104 is a counting pawl 108 normally held out of cooperation with a rack 109 by a spring 110 holding the pawl against the fixed cam stud 111. Rack slide 109 (Fig. 7a) is formed with shoulders fitting in a horizontal groove 112 formed in a guide sleeve member 113 fastened to plate 97. A spring 114 fastened to the front end of the rack slide 109 and the left side of guide 113, tends to hold the rack in the normal retracted position with the extending front end cooperating with a restoring pawl 115. However, every time magnet CT is energized, lever 104 is rocked in a counterclockwise direction and pawl 108 is moved to the right and then drops behind one of the rack teeth on slide 109 and pushes it toward the right. The movement of the pawl is limited to slightly more than one rack tooth space and this gives the release pawl 115 an opportunity to drop behind another tooth and hold the rack in the adjusted position. In the same manner, successive impulses of magnet CT cause slide 109 to move toward the right a distance determined by the number of impulses which in turn are determined by the length of the word about to be recorded.

Since the counting devices are made effective only when the carriage brings the record sheet in the predetermined range near the end of each line, they will be effective only when the contacts 98-99 are operated by cam 95. At such times the blade 100 for operating contacts 99 is over toward the left (Fig. 7) within the range of the end of rack slide 109 which is proportioned to cooperate with the downwardly extending blade 100 (Fig. 5). At the time that the counting slide 109 is moved progressively toward the right in Fig. 7, the contact blade 100 is stationary in its path because the counting operation is not concurrent with the typing operation but prior to the typing operation. Upon typing a word that fits within the selected zone near the end of a line, the contact extension 100 is brought closer and closer to the counting slide 109, so that the space of twenty characters is diminished as small words are recorded until finally a word is analyzed having a larger number of characters and requiring a space greater than the space remaining. The overflow condition is made evident by closure of contacts 99 and initiation of a carriage return operation as described more fully with reference to the wiring diagram.

After the characters of a short word are counted and typing is permitted to take place in the end zone, counting slide 109 is restored so that the space required for the next word may be determined. This restoring operation is controlled by another magnet RE (Fig. 7) also mounted on plate 97 but at right angles to the other magnet CT. Cooperating with magnet RE is an ar-

ture lever 117 pivoted on a stud 118 and carrying the pawl 118 already mentioned. A spring 119 pulls the lever 117 in a counterclockwise direction, and it abuts against the guide 113 in such a position that the pawl 115 normally cooperates with the teeth 102 on rack 109. However, when magnet RE is energized to restore the counting devices, lever 117 is rocked in a clockwise direction and pawl 118 is not only swung back upon its pivot, but it is also carried away by an extending stop on lever 117, so that it is disengaged from the teeth 102 and then spring 114 draws slide 109 back to the normal position shown in Fig. 7. The front end of slide 109 is formed with a tooth of extra height so that the final stopping position of slide 109 can be determined by cooperation with pawl 115 after all the other teeth have passed under the pawl.

The devices for automatically initiating the carriage return and line space functions are shown in greater detail on the wiring diagram (Figs. 13a and 13b) and the mechanisms operated thereby are illustrated in the patents to Hillis 2,104,559 and Crumrine 1,957,322.

The foregoing sections of the description deal with the construction of the typewriter and the additional mechanism coordinated therein to produce the novel results desired. The following sections of the description are concerned with the analysis of the perforated record and the electrical controls operated thereby.

The tapes shown in Figs. 2 and 3 are of the kind formed by a punching mechanism such as that illustrated in the Ayres Patent 2,189,023. The punching machine in said patent is controlled by a keyboard wherein the keys are arranged in a left to right order in the sequence that the letters commonly occur in the words of the English language. The mechanism operated by the stenographic keyboard is designed so that a plurality of keys and a plurality of punches are operable simultaneously to represent many characters at the same time, thereby making it possible to print and punch representations of complete words with one stroke. The tape 34 of Fig. 2 is preprinted with the identifications of all characters. The characters are arranged in three lines because the keys of the stenographic machine are operable with two shift controls in addition to being operable without shift control. The characters represented in the center of the three rows are the characters printed directly without any shift operation. The upper and lower rows of characters are the ones associated with perforations punched when keys are operated along with shift bars. The space X (Fig. 2) bracketed on the side of the tape 34 is the distance that the tape is advanced for each stroke of the stenographic machine, and it also represents the degree of feed used in the sensing devices of the present invention.

Fig. 4 shows an enlarged outline of the character and control perforation positions. At the extreme left of the central row of characters there appears a pair of perforations identified with characters in the shape of an E. The one at the extreme left is the error start control perforation and the second perforation of the center row is the error stop control. At the extreme right of the same central row there is another special control, namely, the "space selecting" perforation 101. Between these error control and space control perforations are all character print control perforations in the center row. At the left side of the upper row it

is seen that eight perforation positions are allotted for typewriter control functions rather than character printing selection. The lower row of perforation positions are devoted to numerical, punctuation and special character representations. In all of the column positions other than the two central vowel representing columns there appears only one of the three perforations. In other words, taking the column representing K, T and *, these three characters are produced under control of only one key along with two different shift operations. Therefore, only one of the three perforations will appear at any one time. In the two central columns of vowel positions it is possible that two of the three perforations may appear in combination in order to represent the vowels i and u in addition to the direct representations of a, e and o by single perforations. The a and e perforations together in the same vertical column represent an i, while the e and o perforations in the same column represent a u. An example of this is seen in a word printed and punched in the tape 36 of Fig. 3. There the word "kind" is represented with the i not appearing directly but represented by the combination of a and e. This tape 36 is produced by an alternative form of punching mechanism shown in the patent to Ayres already mentioned. There the punches not only cooperate with the dies but also carry type faces to place an impression on the otherwise blank tape. The recorded form is easier to read because the only printed characters appearing are the ones that are selected.

Fig. 1 shows the assembly of the Electromatic typewriter EL and a control cabinet CA containing a shelf 120 supporting a tape sensing unit TS. The tape sensing unit is shown in detail in Figs. 9 to 12. In Fig. 9 a motor M is shown fastened to the shelf plate 120 with the motor shaft 121 projecting into a speed reduction gearing unit 122 through which runs a drive shaft 123 for the tape sensing operation. Fastened to the base plate 120 are a series of vertical side frames 124, 125, and 126 carrying bearing hubs for supporting the drive shaft 123. Between the frames 125 and 126 (Fig. 9) is assembled a spool 127 carrying a roll of the perforated tape 34. The spool is formed with a hollow core 128 (Fig. 10), and is readily removable because one of the trunnions 129 (Fig. 11) upon which the core is pivoted is fastened to a flexible leaf spring 130, so that the short trunnion may be withdrawn from the spool whenever it is desired to replace the roll of perforated tape. In Fig. 10 it is seen that the tape is drawn off the roll and directed downward around a pair of feeding sprockets 132 fastened to a shaft 133 pivoted in the side frames of the unit. The direction of the tape is then changed, and it is moved horizontally toward the right and over a table made of insulation material 134 and over a conducting plate 135 embedded in the top of the table. Directly above the plate 135 are three sets or rows of sensing brushes 136 which are spaced to conform with the vertical spacing of the perforation positions shown in Fig. 4. These brushes 136 are provided to cooperate with character counting mechanism for detecting the number of perforations arranged in a horizontal direction across the tape.

As the tape leaves the contact plate 135, it is wrapped around a loop maintaining roller 137 provided to keep the tape taut as character counting operations take place. There are times when

a portion of the tape above table 134 is spaced toward the right without corresponding feeding movements of the tape toward the left under the table 134. Under such circumstances, the paper tape forms a loop such as the loop 138 (Fig. 10) extending at the right of the unit to an extent determined by the number of strokes required to record the word at that point on the tape. After the tape passes around roller 137, it continues toward the left under a contact plate 140 embedded in the lower surface of table 134. Cooperating with plate 140 are three sets or rows of printing control brushes 141 spaced to coincide with the location of the three rows of character perforation positions. The loop forming roller 137 is of a small diameter because the succeeding groups of three sets of perforation columns follow directly one after the other, and it is necessary for the first row of one set of perforations to be under the right row of brushes 136, while the last row of perforations of the preceding group of representations are under the left row of brushes 141. When single stroke words follow directly one after the other, the tape appears as shown in the full line in Fig. 10 with the perforations relating to one word appearing under the print control brushes 141, while the perforations relating to another word are under the character counting brushes 136. However, when the word requires more than one stroke and when its representations occupy more than one tape area, then feeding is suspended with relation to print control brushes 141 while feeding continues past the counting brushes 136 and the tape forms a loop 138, the length of which is determined by the length of the word and the number of strokes it requires.

After passing over the brushes 141, the tape 134 continues to move toward the left and around a pair of sprocket wheels 142 secured to a shaft 143. After leaving the sprocket wheels 142, the tape moves downward and is coiled within a square box 144 formed by thin metallic sheets between the side frames 125 and 126. The loop controlling roller 137 (Fig. 10) extends across the unit between the side frames and is carried by a pair of levers 146 pivoted at 147 on ears extending from the side frames. Springs 148 are attached to the upper end of levers 146 and tend to rock them in a counterclockwise direction to pull roller 137 toward the right. This tension serves to hold the tape taut between the pairs of feeding sprockets 132, 142. Extending in the path of rocking movement of levers 146 is a pair of contacts 150, the blades of which are mounted on insulation blocks attached to a lug in one of the side frames. The operation and control of contacts 150 are explained further in connection with the wiring diagram.

The shafts 133 and 143 (Fig. 11) on which the feeding sprockets are attached are extended beyond the side frame 126 and provided with clutching devices for making the tape feeding operation selective under control of a pair of magnets CF and PF, the former controlling the operation of shaft 133 and the sprockets 132 (Fig. 10) to move the tape for counting operations, and the latter controlling a clutch for shaft 143 (Fig. 11) and sprockets 142 (Fig. 10) for controlling movement of the tape past the print controlling brushes. In Fig. 9 it is seen that a driving pinion 152 is secured to the end of drive shaft 123. This pinion meshes with an idler gear 153 loosely pivoted on a stud 154 extending from the side frame 126. Gear 153 is constantly rotating and

meshes with a pair of clutch gears 186 and 188 also constantly rotating on the tape feed shafts 133 and 143, respectively. Attached to gear 186 is a notched disk 187 in alignment with a clutch pawl 187 normally out of engagement and pivoted on an arm 188 secured to the sprocket shaft 133. The pawl 187 is held disengaged by an armature lever 189 pivoted at 188 and normally rocked in a counterclockwise direction by spring 191 to hold it out of engagement with the magnet CF. Whenever the magnet is energized, lever 189 is rocked in a clockwise direction to release pawl 187 and allow the clutch to be connected so that shaft 133 is rotated through one complete revolution in a counterclockwise direction. The size of sprockets 132 and 142 (Fig. 10) is proportioned so that each revolution thereof is equivalent to the space X (Fig. 2) covering a length of tape area equivalent to one character or control section.

A similar set of clutch connections is interposed between the shaft 143 (Fig. 11) and the print controlling feed magnet PF. A clutch pawl 192 is operated by an armature lever 193 whenever magnet PF is energized. Engagement of the clutch connects the sprocket shaft 143 to the drive pinion 156 and the shaft is rotated one complete revolution in a counterclockwise direction. This serves to advance the record sheet after typing operation in order to bring a new perforated section under the typing control brushes 141. The advance section of the tape is pushed down into the storage box 144.

While the record tape is stationary under the sets of brushes 138 and 141, a reading of the perforations is taken by commutator devices connected to the brushes. Two sets of commutator devices are provided, one set for reading impulses through the upper character counting brushes 138 and the other set for reading the perforations sensed by the lower print controlling brushes 141. In Fig. 9 the commutators 164 are arranged in a bank of three rings in front of which is fastened a special ring 164s. This set of four rings is associated with the counting brushes 138 (Fig. 10), and the commutator segments 167 (Fig. 9) are connected separately to the brushes. There is one ring for each column of brushes and the extra ring 164s is connected to the error start, error stop and space control perforations which do not enter into the counting operation. Certain of the other segments 167 are made inoperative also because they do not concern the character representing features of the tape, and therefore should not be counted along with the characters. In Fig. 4 it is seen that the eight perforation positions in the upper left hand corner of the diagrammatic showing, all relate to special operations of the typewriter rather than character printing representations. Coinciding with these perforation positions is a notch 189 (Fig. 12) cut into the contact plate 135 underlying the character counting brushes 138. The space cut out to form notch 189 is filled with the insulation material in which plate 135 is embedded and the counting brushes overlying the notched position fail to convey any impulses, regardless of the nature of the perforated representations. The action of the commutator reading devices is equivalent to a left to right analysis of the three rows of perforations shown in Fig. 4.

Cooperating with the commutator rings 164, 164s (Fig. 10) is a set of four contact arms 170 fastened to a shaft 171 held by bearings in the

frames 124 and 125. Fastened on the ends of arm 170 are four contact blades 172 cooperating with the inner concentric surfaces of the commutator rings and wiping in a clockwise direction (Fig. 10) to contact the inner ends of segments 167. Also fastened to shaft 171 is an operating gear 173 in mesh with an idler gear 174. Another idler gear 175 connects the train of gearing to a clutch gear 176 loosely mounted on the drive shaft 123. A clutch 177 shown generally in Fig. 9 is operated under control of a magnet CS for driving the commutator devices whenever a character counting operation is initiated. The counting clutch is similar in construction to the clutch about to be described in connection with the printing control commutators shown in detail in Fig. 10.

As already explained, the machine is provided with a set of commutators 165, 165' and 165" for conveying impulses from the perforations sensed by the printing control brushes 141 (Fig. 10). These three commutators are somewhat similar in construction and operation to the other four commutators 164 associated with the character counting brushes. The segments 166 embedded in rings 165 are wired separately to the brushes 141, there being one ring for each column of brushes, all the segments for each column of brushes being confined within an arc of 180° on the ring. The compact arrangement of the segments is possible because the commutator reading devices including a double-ended brush holder 179 (Fig. 10) which is turned through a half revolution for each operation of the machine. The three rings are insulated from, but fastened to, the outer side frame 124 by a pair of screws 180. They are held concentric with shaft 181 to which the brush holder 179 is fastened. The ends of holder 179 carry contact blades 182 for sliding along the inner surface of the rings 165 and contacting successively with the segments 166. Shaft 181 is mounted between bearings in the frames 124, 125 (Fig. 9) and carries a large operating gear 183. In mesh with gear 183 is a clutch gear 184 loosely mounted on the drive shaft 123. Fastened to gear 184 is a circular plate 185 with a pivot 186 carrying a clutch pawl 187. The pawl is normally disengaged from a notched clutch disk 188 fastened to shaft 123. A spring 189 tends to call the pawl 187 into engagement with disk 188, but it is normally prevented from doing so by the hook end of an armature lever 190 pivoted at 191 on the frame 125. Cooperating with the armature lever is a magnet PS which is energized whenever a print control operation is desired. Upon energization of the magnet, lever 190 is rocked in a clockwise direction (Fig. 10), pawl 187 is released to engage disk 188, and the counterclockwise movement of shaft 123 is imparted to gear 184, and gear 183 then turns brush holder 179 a half revolution in a clockwise direction. Spring 192 tends to restore the armature lever and lock out the clutch pawl after each cycle of operation. The construction of the clutch shown in Fig. 10 associated with the print controlling commutators is similar to the clutch directly behind it associated with the character counting commutators. However, it will be noted that the gear ratio of the driving connections for shaft 171 is a 1:1 ratio rather than the half revolution connection made with shaft 181.

The print controlling commutator devices are provided with means for sending an impulse at a time near the end of each cycle of operation. Connected on the outer end of shaft 181 (Fig. 10)

is a cam 194 formed with a pair of equally spaced extensions for striking an insulation block on one of a pair of contact blades mounted on a bracket 195 fastened to frame 125 and holding contacts 196. The extensions are situated so that they strike the block near the end of each typing operation and close contacts 196. The operations initiated by electrical impulses directed through the magnets, commutators and contacts already described will now be pointed out with reference to the wiring diagram.

The wiring diagram

Figs. 13a and 13b together comprise a showing of the electrical connections in and between the tape sensing devices and the automatic typewriter. The showing in Fig. 13a is directed primarily to the connections of the counting control brushes 136 and the relays for controlling tape feeding, type operation and carriage movement. Fig. 13b is devoted in the main part to a showing of the wiring connections between the printing control brushes 141 and the solenoids for operating the typewriter keys.

Referring to Fig. 13a, it is noted that a power source P is located between two main lines 200 and 201 and in series with a switch SW2 that is opened while a blank record sheet is being inserted around the platen of the typewriter and while the perforated tape is being threaded through the sensing unit. After the operator has positioned the blank page in the typewriter, he then threads the tape around the feed sprockets 132, 142 (Fig. 10) under the brushes 136, around the loop sensing roller 137, and under the other brushes 141. And then, after the typewriter carriage is moved to the right, the machine is ready for operation with the first set of perforations under the counting brushes 136. The operator first closes the line switch SW2, and then closes the switch SW1 in series with the motor EM of the "Electromatic" machine, and closes switch SW3 in series with the motor M of the sensing unit and finally closes the switch SW4 in a bell-ringing circuit.

Typing to the left of the twenty character control area

Depression of the start key ST (Fig. 13a) closes contacts 202 and senses a circuit through a starting relay SR. The circuit passes through a contact 203 which is associated with a relay SL that is concerned with the length of sheet control operative upon passage of the end of the sheet. The starting circuit includes line 201, wire 204, contacts 202, relay SR, wire 205, contacts 203, wires 206 and 207 to line 200. Upon energization of relay SR a pair of associated contacts 208 and 209 are closed.

The closure of contacts 209 completes a circuit through the contacts 150 associated with the lever 146 (Fig. 10) of the loop sensing roller and then on to the count feed clutch release magnet CF. The circuit includes line 201, wire 204, contacts 202, contacts 209, wire 211, contacts 150, wire 212, magnet CF and wire 213 to line 200. The other contacts 208 closed by starting relay SR serve to initiate energization of the type feed clutch release magnet PF by means of a circuit including line 201, wire 204, contacts 202, contacts 208, wire 214, contacts 91, wire 215, wire 216, magnet PF, wire 326, and wire 213 to line 200. The energization of the two feed control magnets CF and PF (Fig. 11) serves to operate the clutches

for connecting the sprockets 132 and 142 (Fig. 10) to the drive shaft, so that the sprockets are rotated one revolution and the tape is advanced from one section to another. The feeding operation brings the first punched section of the tape beneath the type sensing brushes 141.

Cam contacts are associated with the feed clutch shafts 133 and 143 (Fig. 11) for operating the commutator brushes. These cam contacts 10 are provided to initiate other operations upon the termination of the tape feeding operations resulting from energization of clutch magnets CF and PF as already mentioned. Referring to Fig. 13a, it may be pointed out that a cam 218 is 15 mounted on the count sprocket feed shaft 171 and two other cams 220 and 221 are mounted on the typing feed shaft 143. The contacts 223 and 224 associated with cams 220, 221, respectively, are closed momentarily near the end of the tape 20 feeding operation relative to the typing brushes 141. The other contact 222 is operated by cam 218 after tape feeding relative to the counting brushes 136. Since contacts 222 and 224 are 25 connected in series, when they operate simultaneously, there can be no circuit directed therethrough. Since contacts 223 are operated by a cam 220 on shaft 143 of the type feed sprocket whenever a feeding operation takes place, the contacts are closed near the end of the operation 30 to initiate a printing cycle through the energization of the typing clutch magnet PS for calling the printing commutator into operation. The circuit through the clutch magnet passes through line 201, wire 226, contacts 223, magnet PS, and 35 wire 227 to line 200. The operation of magnet PS (Fig. 9) causes the type commutator brush holders 179 (Fig. 10) to turn through a half revolution. In so doing, they sense all the holes in the tape under brushes 141 and energize the solenoids for the character or control keys in the typewriter.

The solenoids 40 (Fig. 5) for operating the type bars in the typewriter, are connected directly to commutator segments 168 (Fig. 13b) located on the commutator ring directly opposite the segment 166 connected to the brush 141 for detecting a character perforation corresponding to the type operated by the solenoid. Taking the letter R, for example, and tracing the wiring connections for operating the R solenoid, they can be seen to include line 201, contact plate 140, the brush 141 at the R position, wire 230, segment 166, contact brush 182, brush holder 179, the opposite contact brush 182, segment 168, wire 231 50 leading to the R solenoid, wire 232 common to all the alphabet character solenoids, and then through wire 233 to contact 234 associated with the capitalization control solenoids, and then through wire 282 and wires 236, 237 (Fig. 13a), through error control contacts 238 normally closed and wire 239 leading to the opposite line 200. The returning lead connections of the control solenoids and special character solenoids shown at the right in Fig. 13b do not pass through the capitalization control contacts 234 but are connected directly to the common lead 237 extending to contacts 238, Fig. 13a, and thence to the opposite side of the line.

The vowel segments 168 (Fig. 13b) relating to A, E, O are connected to relays AR, ER, OR so that they may be energized in five different combinations to select the printing of I and U in addition to the direct selections. The vowel relay 70 AR is connected to a wire 241 which is attached

to the two segments 168 of the commutator 165' cooperating with the two sensing brushes 141 located near the center of the column of brushes cooperating with the upper row of perforation positions (Fig. 4).

The second vowel relay ER (Fig. 13b) is in series with a wire 242 having four connections to segments in the commutators 165 and 165'. In addition to the connections to the E segments 168 located to cooperate with the centralized pair of E sensing brushes 141 located in the commutator 165 relating to the central row of perforations, there are two other E connections for the final E's found near the right end (Fig. 4) of the upper two columns of perforation positions. A wire 243 (Fig. 13b) leads to wire 242 from the segment 168 in commutator 165' to detect the final E when it appears in the top row of perforations, and another wire 244 connected in the center commutator 165 is fastened to a segment 168 opposite the segment 168 leading to the final E brush 141 for detecting an E perforation at the right of the center line of perforations.

The third vowel relay OR is connected to a wire 245 leading to the centralized segments 168 in the commutator 165'' in a position to detect the appearance of a perforation in either of the two O positions in the bottom column of positions in the perforation area.

If a relay AR, ER or OR is operated singly, the corresponding vowel type solenoid 40 for A, E or O will be energized. The connection from the A solenoid 40 includes a wire 247 passing through a normally closed contact 248 associated with the E relay ER and continuing through wire 249 to a contact 250 closed by the energization of the A relay AR. The circuit continues through wires 251 and 252 leading to the line 201. The vowel solenoids are connected to the other line 200 by wires to common line 232, and then through wire 233, contacts 234, wires 282, 238, 237 (Fig. 13a) contacts 238 and wire 239 as already pointed out.

The E solenoid is connected to a wire 253 leading to a normally closed contact 254, a wire 255, wire 256, contact 257 closed by the relay ER, wires 258 and 252 leading to line 201.

The solenoid 40 relating to the control of typing the vowel O is in series with a wire 260, and the circuit therefrom passes across a normally closed contact 261 and through a wire 262 leading to a contact 263 which is normally opened but closed by a relay OR whenever a O perforation is sensed. The O selecting circuit continues through wires 264 and 252 to line 201.

The foregoing examples concern the selection of solenoids for typing A, E and O when these vowels are selected by a single perforation. However, the other two vowels I and U are selected when combinations of A and E and E and O are perforated in the record tape. The contacts associated with the relays ER, AR are so shifted, when both are operated simultaneously, that a through connection is made for a circuit to the I solenoid. The circuit may be traced through the U solenoid 40, wire 266, contacts 267 closed by relay AR, wire 268, wire 256, contacts 257 closed by relay ER and wires 258 and 252 to line 201.

Another circuit is set up by the joint energization of relays OR and ER to direct a circuit through the U solenoid along a path including wire 270, contacts 271, wire 255, wire 256, contacts 257 and wires 258 and 252 to line 201.

From the foregoing, it is apparent that the five vowel solenoids 40 are energized by connections established through the detection of single or

double vowel control perforations in the record tape.

Automatic shift for special characters

5 Special characters, such as \$, (, &, etc., each require shifting to the upper case automatically and the holding of this shift while the character is being typed. The control for automatic shifting is accomplished by providing a series of special 10 commutator segments 168' located in the commutators 165' and 165'' in positions to convey current through the brush holders 179 when perforations are sensed corresponding to the special characters. Since there is no special character 15 representations in the center row (Fig. 4), the central commutator 165 (Fig. 13b) is without special segments 168'. The other commutator 165' contains normally two such special segments allotted to the \$ and (marks. These two special 20 segments 168' are connected by a wire 274 with a large number of special segments placed in commutator 165'' to take care of the large number of special signs noted in the lower row of index positions in Fig. 4. Cooperating with the 25 special segments are auxiliary sensing brushes 182' fastened on the commutator levers 179 found in the two commutators reading the special character perforations. These special brushes 182' are set on the brush holding arms 179 in an advanced position, so that when a special character 30 perforation is sensed, they contact the special segment 168' prior to the time contact is made between the ordinary brush 182 and the regular letter selecting segment 168. In this way the 35 shifting key of the typewriter is operated prior to the operation of the printing control key in order that the selected shift character can be impressed on the record sheet.

An example of the shift circuit control may 40 be traced assuming that a perforation is found related to the mark \$. The circuit passes through line 201 (Fig. 13b), plate 140, the \$ sensing brush 141, wire 215, segment 166, contact brush 182, the contact holding lever 179, special contact 45 brush 182', the special segment 168' at the right in the commutator 165' and then through wire 214 and the other special segments 168' in commutator 165'' and through wire 273 to the shift control solenoid 40SH, common wire 237 (Fig. 13a), contacts 238 and wire 239 to line 200. In Fig. 6 is shown how the solenoid 40SH operates a train of connections to pull down the shift key.

Each segment 168 is so located and proportioned as to agree with the timing of contact between brush 182' and segment 168' and therefore is of greater length or advanced with respect to the related segment 168.

Capitalization

60 Devices are provided to capitalize an entire word or an entire line with the control held automatically until a perforation is sensed in the tape in the capitals stop position (Fig. 4). The initiation of complete capitalization is started by 65 the sensing of a perforation in the first index position at the left in the upper row shown in Fig. 4. When the brush 141 at the extreme left (Fig. 13b) senses a perforation in the capitals start position, a circuit is directed through the commutator to the shift lock solenoid 40SL. The circuit can be traced in Fig. 13b, through line 70 201, plate 140, brush 141 and wire 271 at the extreme left, segment 166, brush 182, holding lever 179, brush 182, segment 168, wire 278, shift lock 75 solenoid 40SL, wires 279, 281 (Fig. 13a), contact

238, wire 239 to line 200. The energized solenoid 40SL then operates connections shown in Fig. 6, to pull down and lock the shift lock key.

Typing continues with all characters capitalized until a perforation is sensed in the tape in the capitals stop position. Connected to the segment 168 located opposite the segment 166 connected to brush 141 for sensing the capitals stop position is a wire 281 which is connected to the shift solenoid 40SH in parallel with the wire 273 for conveying selected shift impulses. The shift circuit continues through wire 237 (Fig. 13a), contacts 238, wire 239 and line 200. Upon energization of the solenoid 40SH, the shift key is operated and the shift lock is mechanically released to return the typewriter to the lower case condition.

In order to take care of the other conditions involving capitalization wherein the first word of a paragraph or sentence is to be capitalized, the control tape is provided with a "1st capital" position wherein a perforation causes the shift to be automatically operated along with the recording of a single character. The circuits set up by the 1st capital control is somewhat similar to the capitals start circuit. However, the corresponding segment 168 (Fig. 13b) is attached to a wire 284 leading to a CAP 1 relay connected by wires 282 and 236 to the common wire 237. Whenever the CAP 1 relay is energized, its associated contacts 283 are closed and a holding circuit is established through the normally closed contacts 285 for the relay and the shift control solenoid 40SH. The holding circuit for the relay may be traced through line 201, wire 252, wire 286, contacts 285, wire 287, contacts 283, wire 288, relay CAP 1, and wires 282 and 236 to the common wire 237, contacts 238 (Fig. 13a) and wire 239 to line 200.

At the same time that contacts 283 (Fig. 13b) are closed by the relay, other contacts 289 are also closed to complete a holding circuit through the shift solenoid. This shift circuit includes line 281, wires 252, 286, contacts 285, wire 287, contacts 283 and 289, wire 290, wire 281, solenoid 40SH, common wire 237, contacts 238 (Fig. 13a) and wire 239 to line 200.

The holding circuit is provided to maintain the position of the shift key during the time that the tape is passing from control for shifting, over to control for typing a selected character. Upon establishment of a circuit for controlling the typing of a character, the relay CAP 2 (Fig. 13b) is energized to break the circuit through the holding relay CAP 1. It will be remembered that usually the character print selecting impulses pass through normally closed contacts 234 associated with the CAP 2 relay. However, when relay CAP 1 is active, other contacts 234' are closed to direct the character impulses through wire 235, relay CAP 2, wire 236 and common wire 237, etc. It is through such energization of the relay CAP 2 that the other holding contacts 285 are opened to break the shift circuit after the first capital has been printed. The circuit through the CAP 2 relay is similar to the one traced hereinbefore with relation to printing the character R. When the contacts 285 are opened, the CAP 1 relay is deenergized and the shift solenoid 40SH is deenergized to return all control to a lower case condition.

Tabulation controls for automatic indentation

A series of three magnets are provided and connected to the commutators to sense the tabulating control perforations identified in the

upper left hand corner of Fig. 4 as the TAB 1, TAB 2, TAB 3 index point positions. These automatic controls are provided, respectively, for the indentation of paragraphs, the indentation of the closing of a letter and for the typewritten name or title beneath the signature. A sample tabulation control circuit may be traced in Fig. 13b to show the kind of connection furnished for this form of control. A certain segment 168 is related to the position of the opposite segment 166 connected to the brush 141 for detecting TAB 1 control perforation. This segment 168 is connected to a wire 292 which at its lower end is attached to the magnet TAB 1. Also connected to this magnet is a wire 283 attached to the ordinary tab key magnet TAB en route to the common wire 237. Upon detection of a tabulating control perforation, the TAB 1 magnet (Fig. 8) is energized and an arm is placed in the path of the pivoted stop 62 held on the carriage of the typewriter.

Rather than have a plurality of movable stops on a carriage cooperating with a single fixed stop on frame, the present construction, as shown in Fig. 8, comprises the use of a single point of reference on the carriage. A feature of the construction shown in Fig. 8 is the use of an over-center spring to hold the attracted stopping arm 63 in an effective position. It is maintained there until struck by the stop on the carriage. Then the arm is restored as the carriage is stopped and the usual escape mechanism takes over the control.

The controls for TAB 2 and TAB 3 operation are similar in all respects as that explained in connection with TAB 1 operation, except for the use of other magnets for different extents of carriage movement.

Line spacing control

A line space control magnet LS (Fig. 13a) is provided to feed the record sheet vertically without spacing it horizontally. In the ordinary "Electromatic" mechanism, action of the carriage return key causes both the carriage to be restored and the platen to be rotated to advance the record one line space. For the purpose of the present invention, the construction is altered so that the carriage return key continues to perform both of these functions, and in addition thereto the mechanism for advancing the platen can be separately actuated by the magnet LS. The control is initiated by a perforation near the upper left hand corner of the control section shown in Fig. 4. There it is seen that the third perforation position from the left is identified as the line space position. When a perforation is sensed in the line space position, a circuit is set up to include the segment 168 (Fig. 13b) connected to a wire 295 (Fig. 13a). The circuit passes through switch SW5, magnet LS, wire 294, error stop contacts 238, wire 239 and continues through the line 200. The kind of operation effected by the energized magnet is similar to that specified in the Carroll Patent 2,199,556 wherein a solenoid operates a line spaced pawl.

Operation of switch SW5 is possible to disable plain spacing control. Another switch SW6 is provided in series with a wire 291 and the carriage return magnet 40CR, so that a complete return and spacing operation can be performed if desired.

In all the circuits described, it is understood that rectifiers are to be used in all situations where back circuits are likely to occur.

Typing within the word fitting control area

Since it is difficult for the stenographer to know ahead of time, when taking dictation on the stenographic punch, how the words of printed matter will be fitted into the length of line allotted for the width of the sheet, the initiation of carriage return control must be determined automatically in the typewriter. For this purpose there is provided an adjustable contact carrying block 86 (Fig. 7) adjustably secured to the carriage of the typewriter. The position of the block is adjustable for varying the margin requirements. The carriage in escaping to the left, comes to a point where the contact operating projection 94 rides over the cam bar 95 on a fixed part of the carriage frame. Then, the contacts 90 to 93 are shifted to initiate character counting operations, so that all the words that are about to be typed are fitted in the space remaining near the end of a line, before carriage return operation is initiated.

Operation for a single stroke word.—The number of character counting operations vary according to the number of tape sections devoted to the representations of a single word. When more than one section is required to represent a word, the space perforation is not found in the first section. For all short words, the representations of which are punched in a single stroke, the space perforation is punched in the same control area. It is in connection with such single stroke representations that the present portion of the description of the character counting operation is concerned. When the carriage has escaped far enough to the left so that the positions of the contacts have been changed by the camming operation already pointed out, the counting of all subsequent words to be typed on the same line first occurs automatically.

As the machine operates for automatic typing, the commutator shaft 181 (Fig. 10) is turned through a half revolution and near the end of the operation, cam 194 closes contacts 196. These contacts 196 (Fig. 13a) are in series with the magnet CS (Fig. 9) for calling in the counting commutator drive. The circuit closed by contacts 196 includes line 201 (Fig. 13a), wire 296, contacts 196, wire 297, normally closed contacts 298, wire 299, wire 300, normally closed contacts 301, wire 302, magnet CS, wire 303, contacts 93, wire 304 and line 200. When magnet CS is energized, the clutch 177 (Fig. 9) is connected and the counting commutator brush arms 178 (Fig. 10) are turned through a complete revolution.

Although only one semicircular arrangement of commutator segments 167 is shown in Fig. 13a, with a contact arm 178 pivoted to wipe over them in succession, it will be remembered that there are three such arrangements, superimposed one over the other as shown in Fig. 9. The three commutator brushes 172, in effect, wipe from left to right across the indicia positions shown in Fig. 4, to count the number of character representing perforations. The eight control perforations positions in the upper left hand corner are not counted by the brush 172 because they are made ineffective by the insulation in notch 169 (Fig. 12) as already pointed out. The two error control perforations at the left of the center row (Fig. 4) are also ineffective to control counting because the brushes 186 (Fig. 10) detecting these perforations are wired to the special commutator 164s (Fig. 13a) rather than to the other three commutators 164.

Now, with the arrangement of the three commutators 164 in mind, it will be apparent that as the arms 178 rotate, an impulse will be sent therethrough for each character perforation found in the area of the tape under brushes 186. The impulses are directed through the counting control magnet CT by a circuit about to be described. Line 21, wire 204, plate 185, brush 186, segment 167, brush 172, arm 178, shaft 171, line 10 388 representing diagrammatically a continuous connection through shaft 171 to arm 178' in the special commutator 164s, continuing through brush 172', contact sector 161c, wire 306, contacts 307, wire 308, magnet CT, wire 309 and line 200. The energized magnet CT (Fig. 7) then operates to pull the pawl 108 and the engaged rack 109 step-by-step to the right a number of steps corresponding to the number of letters represented on the tape area. Since the magnet RE is normally de-energized, the retaining pawl 115 is lowered in position to hold the rack 109 after each step of displacement.

Rack 109 is aligned with one blade of the contacts 99 on the adjustable block 86. When the carriage has moved to the left into the counting zone, a sufficient progression of the rack 109 to the right causes it to run into the contacts 99 and indicate that the word to be printed does not fit in the space that is available. However, if the word on the tape is recorded in one stroke and if the number of letters comprising it is fewer than the number of spaces still available in the line, rack 109 will not close contacts 99 before the end letter of the word is counted.

35 In the case of a single stroke word, the last perforation sensed is that relating to the space desired after the word. A control circuit is set up through the "space" segment in the central commutator 164, Fig. 13a, and the special commutator 164s. The circuit includes line 201, wire 204, plate 185, sensing brush 186 cooperating with the location for hole 101, Fig. 4, on the tape, wire 314, Fig. 13a, end segment 167, brush 172, arm 178, shaft 171, connection 305, arm 178', brush 172', space segments 167s, wire 315, restoring control magnet RE, and wire 213 to line 200.

40 At the same time that the circuit passes through magnet RE, a branch circuit carries an impulse through the space control relay SP2. The circuit is similar to that last described but includes segment 167s, wire 315, wire 316, relay SP2, wire 317, contacts 318, and wire 319 to line 200.

45 Magnet RE, when energized, lifts pawl 115 (Fig. 7) to permit the restoration of rack 109 as urged by spring 114. The operation of the relay SP2 causes the opening of the contacts 298 and 301 in series with the counting clutch magnet CS to prevent its operation during typing. The relay also acts to close contacts 320, 321 and 322. The first mentioned pair of contacts is closed to set up a holding circuit through the relay so that it remains effective after the spacing perforation is no longer sensed. The circuit through the relay then follows the path along line 201, wire 226, contacts 320, relay SP2, wire 317, contacts 318, and wire 319 to line 200.

50 Late in the cycle involving the sensing of perforations, a pair of cam contacts are operated to complete circuits for effecting operations necessary to the completion of the counting function. The cams 310 and 311 are used for operating the contacts 312 and 313. These cams are mounted on shaft 171 which is known to be the shaft carrying the counting commutator arms 178 and 178'. The cams are positioned on shaft

so that they become effective to close the contacts near the end of the cycle. Then, contacts 313 are closed and a circuit is directed through the contacts 322 (already mentioned in connection with the space operation of relay SP2) and magnet PF for controlling the advancing of the tape under the print controlling brushes. The circuit through magnet PF runs as follows: line 201, wire 324, contacts 313, wire 325, contacts 322, wire 216, magnet PF, wires 326, 213 and line 200. The closure of contacts 312 causes a circuit to be set up through the starting relay SR, and a complete connection is formed with line 200, wire 207, wire 206, contacts 208, wire 205, relay SR, wire 327, contacts 312 and wire 324 to line 201. The operation of relay SR causes the closure of contacts 209 and energization of the counting tape feed magnet CF, through a circuit including line 201, wire 324, contacts 312, wire 327, contacts 209, wire 211, contacts 92, wire 212, magnet CF and wire 213 to line 200.

The simultaneous action of magnets CF and PF (Fig. 11) causes operation of both feed clutches, and the connected sprockets operate to advance the record tape through a distance equivalent to one recording area.

As previously explained, this causes simultaneous operation of the three cams 219, 220 and 221 (Fig. 13a), and the operation of contacts 222, 223 and 224. When operated at the same time, contacts 222 and 224 each cancel the effect of the other and prevent a circuit therethrough. However, the other contacts 223 are effective when closed to energize the print control magnet PS for clutching the typing commutator devices to read out and control the printing of the single stroke word which was found to fit within the space available near the end of a line.

Character counting for a multi-stroke word

When the character perforations relating to a word are spread over more than one recording area on the tape, this is indicated by the absence of the space perforation after the first or second area. Then the character counting operations must be continued and repeated section after section until the section is found bearing the spacing perforation. To produce this result, the operation of the counting commutators is alternated with operation of the feeding devices adjacent the counting brushes 136. These counting and feeding operations are carried on without subsequent printing and feeding operations of the tape in association with the typing control brushes 141, because the length of the word must be determined before a printing operation can be allowed to take place. The length of the word determines whether it is to be recorded at the end of one line or at the beginning of the following line. As the successive letters parts of the word are counted, an amount of slack is allowed to accumulate before the tape reaches the print controlling brushes.

Upon completion of the counting operation in connection with the letters recorded in the first tape area, cams 318 and 319 (Fig. 13a) are operated to close contacts 312 and 313. It should be noted that relay SP2 is not energized because no space perforation is sensed at the end of the first count cycle.

Another feature of the multiple stroke sensing operation is that after the first count cycle the rack 109 (Fig. 7) remains advanced in the right hand direction as many steps as there are character perforations in the first stroke of the word.

The closure of contacts 312 causes current to flow through relay SR, along the train of circuit connections described hereinbefore. When relay SR is energized, the associated contacts 209 are closed and a circuit is directed through the counting feed clutch magnet CF. The circuit through magnet CF is also already described hereinbefore. The energization of magnet CF (Fig. 11) causes operation of the clutch associated with the top sprocket wheel 132 (Fig. 10) and, when this wheel is rotated, it feeds the punched tape a distance equal to the height of one stroke representation on the tape.

Since magnet PF (Fig. 11) is not energized at the same time, sprocket 142 (Fig. 10) remains stationary, and the tape forms an extending loop 138 illustrated by the dotted lines at the right of the roller 137 in Fig. 10. As the loop is formed, the loop sensing roller 137 is carried along toward the right as borne by the arms 146 which are tensioned by springs 148. This operation causes the opening of contacts 150 cooperating with one of the arms 146. Upon the completion of the rotation of the top sprocket wheel 132, the cam 218 (Fig. 13a) on the same shaft, operates to close contacts 222 and this provides a circuit for re-energizing the counting clutch magnet CS, through line 201, contacts 224, contacts 222, wire 297, contacts 298, wire 299, wire 300, contacts 301, wire 302, magnet CS, wire 303, contacts 93, and wire 304 to line 200. The energized magnet CS (Fig. 9) operates the clutch connecting the counting commutators and they are operated through another counting cycle.

35 The successive operations of the counting commutators and displacement of the counting rack 109 are continued until either the rack closes contacts 99, or the space perforation is sensed in the right end of one of the character areas on the tape. When the space perforation is sensed, the control is shifted from the character counting operation to the typing operation in the manner previously described.

35 Since the operation required for typing a long word represented on the loop of the tape is different from the recording of a single stroke word, the differences in operation will be described. After the part of the word derived from the first area has been typed, the cam 194 (Fig. 13a) 40 closes contacts 196 and directs a second circuit through the print feed magnet PF. The circuit follows a path through line 201, wire 296, contacts 196, wire 297, contacts 321, wire 216, magnet PF, and wires 326 and 213 to line 200. The operated magnet PF then connects sprocket wheel 142 to the drive shaft while the other sprocket 132 remains stationary. The operation of the lower sprocket alone, serves to reduce the size of the loop 138, and typing continues until a space perforation is detected by the related type control brush 141 and the magnet SP1 is energized to open contacts 318, deenergizing the relay SP2 which then permits contacts 321 to open, breaking the circuit through the printing feed clutch magnet PF.

70 The circuit through magnet SP1 which determines the termination of a word printing series of operations under control of a space perforation, indicating the end of a series of related representations, may be traced at this point. Starting with line 201 (Fig. 13b) and running across plate 140 to the brush 141 analyzing the space index position, the circuit continues through wire 328, segment 166, brush 182, brush holder 179, brush 182, segment 168 at the left of the center com-

mutator 165, wire 328 (Fig. 13a), magnet SP1, and wire 318 to line 200. This circuit is established to terminate printing operations after the typing of each complete word.

Before the space perforation is detected by a print controlling brush, the alternating operation of the clutch magnets PF and PS continues to make it possible to feed the tape and read the tape alternately as long as a loop exists and the parts of the word, short of the last part, continue to advance under the type controlling brushes.

Operation when a word is longer than the available space

When the carriage approaches near the left end of its path of travel and it is found by counting operation that the number of letters in a word exceeds the number of spaces still available at the end of a line, the machine is controlled to prevent printing and automatically operate the carriage return and line space devices to shift the record sheet so that the word found too long for the end of one line, can be typed at the beginning of the following line. The overflow condition causes the rack slide 109 (Fig. 7) to move into cooperation with the contacts 99, closing them and setting up a train of connections about to be explained with reference to Fig. 13a.

There it is noted that contacts 99 are in series with a solenoid 40CR for causing depression of the usual carriage return key in the Electromatic machine. The circuit through the solenoid includes line 201, wire 226, contacts 99, solenoid 40CR and line 200.

The plunger of solenoid 40CR carries an operating member 330 cooperating with a pair of contacts 331 in series with the counting release magnet RE for restoring the counting devices. The circuit for magnet RE follows a path through line 201, wire 226, contacts 331, wire 315, magnet RE, wire 213 to line 200. The energized magnet RE (Fig. 7) then lifts pawl 115 and allows the rack slide 109 to be restored in readiness for another letter counting operation.

Closure of contacts 331 on a carriage return operation also causes energization of relay SP2 to initiate typing. The circuit for relay SP2 established as a result of carriage return operation, comprises line 201, wire 226, contacts 331, wires 315 and 316, relay SP2, wire 317, contacts 318, and wire 319 to line 200. The closure of the contacts 328 associated with relay SP2 sets up a holding circuit therethrough.

Near the end of the counting cycle resulting in a carriage return function, if the cams 310 and 311 (Fig. 13a) close contacts 312 and 313 before the carriage has moved far enough to get out of the twenty letter control region, the contacts 92 and 93 are still closed and an impulse is directed through both feed control magnets CF and PF. The tape will then be advanced by both sprocket wheels and typing will be controlled by the section of the tape brought under the type sensing brushes 141, but the joint action of the sprockets will not reduce the length of the loop of tape previously formed. However, rotation of cam 194 closes contacts 196 and directs current through contacts 321 to magnet PF which causes the lower sprocket wheel to turn alone and feed the tape under the lower brushes, while the upper section of the tape remains stationary. This reduces the length of the loop of tape previously formed.

The rotation of the typing control commutator brushes under control of magnet PS, and the feed-

ing of the tape under control of magnet PF, continue to operate alternately to type and feed until the loop of punched tape is entirely closed. Closing of contacts 180, effected by the loop sensing roller, causes magnets CF and PF to operate simultaneously and connect both sprocket wheels and advance the tape sections in synchronism. The typing and feeding actions continue until the carriage again arrives in the twenty letter control region.

Error start and stop controls

When the operator of the stenographic punching machine desires to make corrections, she punches a spaced pair of error start and error stop perforations (shown at the left in the center row of index points in Fig. 4) at the beginning and ending of the area on the tape in which she wishes the data to be eliminated when used to control the typing machine. The ordinary tape feeding operations continue past such an area, but the special error control perforations cause the elimination of all counting operations and typing operations which would ordinarily take place under control of character perforations in the tape between the points set off by the error start and error stop perforations.

Error control when typing in the part of a line to the left of the control region

While typing is taking place at the beginning of the line, the detection of an error control perforation causes suspension of both counting and typing. The suspension of counting is important at the time, because of the distance between the rack slide 109 (Fig. 7) and the co-operating contacts 99. The separation is so wide that there is no chance of an overflow condition resulting, and the movement and restoration of the rack is accomplished in the ordinary manner. However, at such times it is important that the typing operations be suspended to eliminate the portions of data designated by the error start and error stop control perforations. The control is effected by disabling the return circuit connection from all of the character key operating solenoids. The initiation of such control is started by the detection of an error stop perforation under the related brush 141 (Fig. 13b) and the energization of an error start relay ES1 (Fig. 13a). The circuit set up thereby, follows a path through line 201 (Fig. 13b), plate 140, brush 141 at the left of the center commutator 165, wire 332, segment 166, brush 182, brush holder 179, brush 182, segment 168, wire 333 (Fig. 13a), relay ES1, wire 334, contacts 335, wire 336 and line 200. Energized along with relay ES1 is a reset magnet RE' which resets the counting rack if it is displaced and acts to perform all other resetting functions necessary to error starting. When relay ES1 is energized, it closes associated contacts 337 to establish a holding circuit which then follows a path through the relay as follows: Line 201, wire 338, contacts 337, wire 333, relay ES1, wire 334, contacts 335, and wire 336 to line 200. The relay ES1 is energized and the other contacts 238 associated therewith are open and, since these contacts are in series with the return line 237 running to the solenoids for all the character typing keys, the result is that typing will be suspended beginning with the sensing of the error start perforations.

When the second error control (known as the error stop perforation) is sensed, it is desired that the eliminating controls be dropped and re-

sumption of typing take place in the ordinary manner. The error stop perforation sets up a circuit through a relay EP₁ (Fig. 13a) associated with the normally closed contacts 335. The circuit for error stopping runs through line 201 (Fig. 13b), plate 140, brush 141 second from the left in center commutator 165, wire 339, segment 166, brush 182, brush holder 179, brush 182, segment 168, wire 340 (Fig. 13a), relay EP₁, wire 336 and line 200. Relay EP₁, when energized, attracts its armature and opens contacts 335 to break the connection for the holding circuit through relay ES₁. The deenergization of relay ES₁ allows the closure of contacts 238 and sets up a through connection for the return line 237, whereby all the character type solenoids are again effective to cause typing under control of the perforated tape.

Error control when typing in the control region

Since the counting operations become critical when the end of a line is approached, it is desired that the error controls have some effect to prevent the closure of contacts 99 (Fig. 7) by the counting of letter perforations found in the area of the tape between the error control perforations. In order to prevent the counting of letters that are not to be printed, relay controls are provided in association with the counting commutators to eliminate letter counting operations when an error start perforation is sensed. The counting elimination controls are initiated by a circuit through the brushes of commutators 164 and 164s (Fig. 13a). The error start control includes line 201, wire 204, plate 135, brush 136 at the left of commutator 164, wire 341, segment 167, brush 172, arm 170, connection 305 to arm 170', brush 172, error start segment 167t, wire 342, relay ES, contacts 343 and wire 309 to line 200. Then the energized relay ES forms a holding circuit by the closure of contacts 344. The holding circuit may be followed through line 201, wire 226, wire 345, contacts 344, relay ES, contacts 343 and wire 309 to line 200.

The other contacts 307 associated with relay ES are normally closed in series with the counting control magnet CT for conveying an impulse for each letter perforation detected. However, as soon as relay ES is energized denoting error start control, contacts 307 are opened to prevent the flow of counting impulses, thereby suspending the operation of rack 109 (Fig. 7) during the interval in which the tape is sensed between the error start and error stop perforations.

When an "error stop" perforation is detected, the holding circuit through relay ES (Fig. 13a) is opened and contacts 307 are allowed to close and again make counting operations effective. A relay EP is energized to effect error stop control by a circuit including line 201, wire 204, plate 135 (second from the left on commutator 164), wire 346, segment 167, brush 172, holder 170, connection 305, holder 170', brush 172, error stop segment 167p, wire 347, relay EP and wire 309 to line 200. Relay EP, when energized, opens contacts 343 and breaks the holding circuit through relay ES. The deenergization of relay ES causes the closure of contacts 307 and the counting circuit is reestablished through magnet CT. All perforations following the error stop perforation are to be counted because they are effective to control typing and letter spacing in the usual way.

Automatic sheet length control

While the stenographer is operating the stenographic punch she cannot readily determine when the data she has recorded will complete a typed record sheet. Therefore, mechanism is provided in the typewriter to sense this condition automatically. A thin, narrow band of metal 349 (Fig. 13a) is wrapped around the platen 18 as a ring located under the margin of the typed sheet. 5 record sheet. Therefore, mechanism is provided in the typewriter to sense this condition automatically. A thin, narrow band of metal 349 (Fig. 13a) is wrapped around the platen 18 as a ring located under the margin of the typed sheet. This band is placed in the margin so that it will have no effect on the appearance of the typed impressions which are ordinarily formed by impact against a yielding rubber surface. In the end view of the platen shown in Fig. 13a, a lever 15 350 of insulation material is shown to carry two conducting rollers 351. These rollers are spaced apart on lever 350 but mounted in the same plane so that they both overlie the band 349 and they are in contact with it when there is no paper around the platen. However, when a record sheet is inserted, the paper acts as an insulator preventing a circuit from passing between rollers 351.

As the platen feeds the paper vertically, the 20 bottom edge of the sheet will ultimately pass to the left out from under the rollers, allowing them to contact the metallic band 349. The roller lever 350 is mounted to be adjustable so that the amount of unused space to the left at the 25 bottom of each record sheet can be varied according to the wishes of the operator. Wires are fixed to bearings for metallic pivots on rollers 351. When the rollers 351 contact the band 349, current flows through the relay SL to set up a 30 sheet length control circuit. The circuit passes through line 201, wire 353, roller 351, band 349, the other roller 351, wire 354, relay SL, wire 355, contacts 356, wires 357, 206 and 207 to line 200. Relay SL then establishes a holding circuit by 35 the closure of contacts 358. The holding circuit passes through line 201, wire 204, contacts 358, wire 354, relay SL, wire 355, contacts 356 and wires 357, 206 and 207 to line 200. Relay SL also 40 proceeds to open contacts 360 normally closed in 45 series with the typing control motor M. The resulting deenergization of the motor causes suspension of all tape sensing and typing control until a new sheet is inserted to break the connection between rollers 351.

50 At the same time that relay SL is energized, a bell B is activated to signal to the operator that the machine needs to have a new record sheet inserted. The operator can turn off a switch SW4 in series with the bell to silence it while the new sheet is being inserted.

55 After the operator has put the new record sheet in the machine, she presses the start key ST to break down the circuit through the sheet length control relay SL. When the start key is depressed, it operates contacts 356 to open them and break the holding circuit through relay SL. The deenergization of the relay allows the restoration of contacts 360 to the normally closed condition in series with the motor M which is thus made effective again to drive the connections for tape sensing and record typing operations. Following this, the operator may again close switch SW4 if she wishes to be automatically summoned when the end of the new page is reached.

Stopping the machine

60 A stop key SP is provided so that the operator can stop the machine at any time during the 65 various phases of operation. This key controls 70

the closure of contacts 362 in series with the sheet length relay SL. The stopping circuit through relay SL includes line 231, contacts 362, wire 354, relay SL, wire 355, contacts 356 and wires 357, 206 and 207 to line 200. The relay 5 then opens contacts 360 to disable motor M and closes contacts 358 to set up a holding circuit as already described. Subsequent starting operation is initiated by depression of the start key ST as already mentioned.

While there have been shown and described and pointed out the fundamental novel features of the invention as applied to a single modification, it will be understood that various omissions and substitutions and changes in the form and 10 details of the device illustrated and in its operation may be made by those skilled in the art, without departing from the spirit of the invention. It is the intention, therefore, to be limited only as indicated by the scope of the following 15 claims.

What is claimed is:

1. In a printing machine controlled by a perforated tape, said tape having a column of three index positions for holding the combinations of one or two perforations representing the five vowels, means for sensing said three index positions, a set of three relays operated singly or in combinations of two under control of said sensing devices, a set of five vowel printing members, means for operating said printing members, five electrical devices for controlling the operation of said members, and labyrinth circuits connected to said five electrical devices and having contacts operated by said three relays to make one device effective for recording a vowel representation.

2. In a printing machine controlled by a record tape bearing data representing indicia, a series of individual sensing devices for analyzing the indicia on the tape, means for feeding said tape to bring said indicia into cooperation with said sensing means, a set of printing members, operating means therefor including commutator devices having connections to said sensing devices, said commutator devices having a movable contact structure, a main operating means, a clutch between said main operating means and said commutator contact structure, and means under control of said feeding means for operating said clutch to control sensing.

3. In a machine for printing justified lines of words on a record, a carriage for holding said record, printing devices, means for entering the letters of a word, means under control of said entering means for operating said printing devices, means for letter spacing said carriage relative to said printing devices, adjustable justification controls cooperating with said carriage for a predetermined extent near the end of each line of print, means cooperating with said entering means for making a preliminary determination of the length of a word about to be printed, means under control of said controls and preliminary means for comparing said determined word length with said predetermined extent of line length of said justification controls, and means under control of the last mentioned means for suspending operation of said print operating means when a word is longer than the space at the end of a line.

4. A machine as set forth in claim 3 with carriage return mechanism, means for automatically operating said return mechanism as an incident to suspension of printing, and means for resuming printing at the beginning of a new line.

5. In a printing machine controlled by a record tape for printing justified lines of data on a record sheet, said tape bearing indicia arranged in successive areas to represent the letters of words, means for feeding said record tape, a pair of sensing devices located in the path of said tape and cooperating with the indicia of successive areas thereon, letter counting devices controlled by one of said sensing devices which is the first to cooperate with the tape, printing devices, print control devices cooperating with the second of said sensing devices for operating said printing devices, a carriage for holding said record sheet, escapement mechanism for letter spacing said carriage, justification controls adjusted to cooperate with said carriage within a predetermined number of letter spaces from the end of each line, comparing devices rendered effective by said justification controls and cooperating with said letter counting means to determine if the word about to be printed is short enough to fit within the remaining area near the end of a line, carriage return and line space mechanisms, means under control of said comparing means for suspending operation of said printing devices and initiating operation of said carriage return and line space mechanisms, whereby a word found too long for the end of one line is printed at the beginning of the following line.

6. In a printing machine controlled by a record bearing indicia representing the letters of words, said record having a plurality of successive areas, each area bearing a plurality of indicia arranged in a left to right order for representing the letters of a word as they appear in a left to right order, a plurality of said areas being devoted to a long word, the end of which is signified by the appearance of a word space indicium at the right of the last related area, means for sensing said indicia, means for feeding said record relative to said sensing means to place the areas successively in cooperation with the sensing means, machine control devices operated continuously under control of said sensing means when cooperating with successive areas of said record, and means under control of said word space indicium for suspending operation of said machine controls.

7. A machine of the kind set forth in claim 6, wherein the machine controls include printing members and automatic operators therefor which are operated successively to print the letters of the word under control of the plurality of areas on the record.

8. A machine of the kind set forth in claim 6, wherein the machine controls include letter counting and space measuring devices operated under control of the sensing means and indicia in a plurality of areas on the tape, means for measuring a predetermined sheet area in which a certain number of letters are to be printed without overflow, means under control of said letter counting devices and said area measuring means for determining if the word to be printed fits within said area or belongs on a new sheet line and means for restoring said counting and measuring means under control of said word space indicium.

9. In a printing machine controlled by a tape bearing data representing indicia and space control indicia separating related data, means for printing on a sheet, means for spacing said sheet, means for selecting an area on said sheet to receive print without overflow, a pair of sensing stations with devices for analyzing said indicia, means for feeding said tape relative to said sta-

tions to pass them successively, means under control of the devices at the first station for measuring an item of data to determine if a printed record of it will fit in said area, means under control of the devices at the second station for controlling operation of said printing means, means under control of the space indicium analyzing device at the first station for suspending operation of said measuring means and initiating operation of said print operating means, and means under control of the space indicium analyzing device at the second sensing station for suspending operation of said print operating means and initiating operation of said measuring means.

10. In a machine for printing words on a sheet according to letter representing indicia on a control tape, a first means for sensing said tape, means under control of said first means for counting said letter indicia, a second sensing means, printing devices, means under control of said second sensing means for operating said printing devices to record words, tape feeding devices normally effective to advance successive tape areas past said two sensing means simultaneously, automatic means for determining when said counting means is effective, and means under control of said automatic means for controlling said tape feeding devices to advance the tape past the first sensing means and then past the second sensing means alternately.

11. In a printing machine for recording on a sheet according to data represented by indicia in a succession of areas on a record tape, printing devices, means for operating said devices, a first tape sensing means, machine controls effected under control of said sensing means, a second sensing means, means under control of said second means for controlling said print operating means, means for feeding said tape past said first sensing means, other means for feeding said tape past said second sensing means, a slack detecting means cooperating with said tape between the two sensing means, and means under control of said detecting means as operated by said other feed means for initiating operation of said first feed means for machine control without printing, said detecting control means also operated by the first feed means to suspend machine control while printing as the tape is fed by said other means.

12. In a printing machine controlled by a record tape bearing indicia in a succession of control areas, print control sensing devices cooperating with one area, count control sensing devices cooperating with the following area, a main operating means, means for feeding the tape past said count sensing devices, a clutch between said feeding means and said main operating means, other means for feeding said tape past said print sensing devices, a clutch between said other feed means and said main operating means, a loop sensing device operated according to the length of tape between the two sensing devices and extended by a plurality of count feeding operations in the absence of print feeding operations, said loop sensing device being operated when the tape is taut due to a continued succession of simultaneous counting and printing, and means under control of said loop sensing device for enforcing alternation of counting and printing by control over said feeding clutches, letter counting devices, a commutator between said count sensing devices and said letter counting devices, movable contact devices in said commutator, a clutch be-

tween said commutator contact devices and said main operating means, means for selectively operating said clutch, printing devices, a commutator between said printing control devices and said print sensing devices, movable contact devices in the last mentioned commutator, a clutch between the last mentioned commutator contact devices and said main operating means, and means for selectively operating said clutch to initiate a printing operation.

13. In a printing machine controlled by a record tape bearing character representing indicia, means for sensing said indicia, said indicia being represented in a plurality of successive areas on said tape, means for feeding said tape to bring area after area into cooperation with said sensing means, a pair of special sensing devices cooperating with a portion of the tape devoted to indicia for representing error start and error stop control, said error control indicia being located by the operator to demarcate one or more areas of said tape for elimination of printing, printing devices, means under control of said character sensing means for operating said printing devices, means under control of said error start sensing device for suspending operation of said print operating means, and means under control of said error stop sensing device for initiating operation of said print operating means.

14. A machine of the kind set forth in claim 13 with the character representing indicia arranged in a left to right order in said tape areas with initial consonant, intermediate vowel, and final consonant representations being arranged in the order mentioned, said error start and error stop sensing devices located to the left of all character sensing devices, and means for making the sensing devices effective in a left to right order.

15. In a machine controlled by a tape bearing control indicia in a plurality of areas and having error start and error stop indicia in two of said areas, means for sensing said control indicia, a special pair of sensing devices for sensing said error indicia, means for feeding said tape past said sensing means and devices area after area, means under control of said sensing means for controlling operation of the machine, an error start relay, an error stop relay, means under control of one special device in cooperation with an error start indicium for energizing said start relay, a holding circuit for said start relay including contacts associated with said stop relay, means under control of said start relay for suspending operation of said machine control means, and means under control of the other special device in cooperation with an error stop indicium for energizing said stop relay to break said error holding circuit.

16. In a machine of the kind set forth in claim 10 wherein the control tape bears error start and error stop indicia located to denote an area of letter representing tape to be ineffective for printing control, means under control of error indicia sensing means in said first sensing means for suspending operation of said counting means, and means under control of error indicia sensing means in the second sensing means for suspending operation of said printing devices.

17. In a typewriter controlled by a record tape bearing character representing indicia arranged in a plurality of successive tape areas with word or word part representations in each area, said tape also bearing capital start indicia and capital stop indicia, a set of type bars in a shiftable basket, case shifting mechanism cooperating with

said basket, means for sensing the character representing indicia, means under control of said sensing means for operating said type bars, means for sensing a capital start indicium, means under control of the last mentioned sensing means for operating said case shift mechanism, means for sensing said capital stop indicium, and means under control of the last mentioned sensing means for releasing said case shift mechanism to assume the normal lower case position.

18. A machine of the kind set forth in claim 17, wherein the capital control devices cooperate with the usual shift and shift lock keys, the capital start means operating to depress the shift lock key and the capital stop means operating to depress the shift key to release the shift lock key.

19. In a typewriter controlled by a record tape bearing a plurality of character representing indicia, said indicia arranged in a left to right order to represent initial consonants, intermediate vowels, and final consonants in the order mentioned, said tape also bearing a special first capital indicium at the left of selected tape areas, each of said areas bearing a word or word part, means for sensing the indicia in an area on the tape, means for feeding said tape to bring said areas in succession into operation successively with sensing means, printing members having upper and lower case type, means for shifting said printing members, means under control of said sensing means for operating said printing members to print on a record sheet, means for sensing said special indicium, and means under control of the last mentioned sensing means for operating said shifting means.

20. In a typewriter controlled by a record tape bearing character representing indicia arranged in a plurality of successive areas, each tape area containing one or more indicia representing a complete word or a word part, said tape also bearing one or more of a plurality of different tabulating control indicia, means for sensing said character indicia, printing devices, means under control of said sensing means for operating said printing devices to print on a record sheet, a carriage for holding said record sheet, a tabulating abutment adjustably secured to said carriage, a plurality of normally ineffective differentially located tabulating stops for cooperating with said carriage abutment, a plurality of separate special sensing means for detecting said tabulating indicia and a plurality of independently controlled operating means controlled by said last mentioned sensing means for making one of said tabulating stops effective to locate said carriage in a selected position.

21. In a printing machine controlled by a record tape bearing character representing indicia, means for sensing said indicia, printing devices, means under control of the sensing devices for operating said printing devices selectively to record data on a record sheet, a carriage for holding said sheet, means for setting a predetermined length of line, means for setting an area near the end of said line for controlling printing within the line, means under control of said sensing means for predetermining the length of a word about to be printed, carriage return mechanism, and means cooperating with said word length determining means and said area setting means for selectively operating said carriage return mechanism before or after the printing of a word.

22. In a typewriter for printing on a record sheet, printing devices, data entry means for controlling operation of said printing devices, means

under control of said entry means and operated preparatory to said controlling means for indicating data about to be printed, a carriage for holding said record sheet, a spacing rack slidably mounted on said carriage, shifting devices cooperating with said rack and operated under control of said preparatory means according to the length of data to be printed, escapement mechanism and data spacing devices, means for releasing said rack under control of said data spacing devices, automatic carriage return mechanism, adjustable means cooperating with said rack and set to predetermine the lengths of lines of print, a cam on said carriage, other settable means cooperating with said cam at a predetermined point when printing approaches near the end of said line, and cooperating with said rack operating means to limit its effectiveness within the area near the end of the line, and means for operating said carriage return mechanism under control of said rack and said line length setting means when data is found to fail to fit within the line.

23. In a printing machine for recording on a record sheet, printing devices, letter selection controls for operating said printing devices, a carriage holding said sheet, carriage return mechanism, means cooperating with said letter selection means for counting the number of letters in a word about to be printed, and means under control of said counting means for operating said carriage return mechanism.

24. In a printing machine controlled by a record tape bearing indicia representing characters and line spaces, printing devices for recording on a record sheet, means under control of said tape for operating said printing devices, a carriage for holding said record sheet, carriage return mechanism, line spacing mechanism cooperating with said sheet, means for sensing said line space indicium, and means under control of said sensing means for operating said carriage return mechanism and said line spacing devices.

25. In a typewriter controlled by a record tape bearing indicia representing lower case characters and special characters, printing devices including upper and lower case characters for recording on a record sheet, means under control of said record tape for operating said printing devices, sensing devices cooperating with said tape for controlling the last mentioned means, said sensing means including commutator devices with spaced segments corresponding to the individual character indicia, certain of said character representing segments having a shift control segment arranged parallel thereto, shift control mechanism cooperating with said printing devices, and means cooperating with said shift segments for operating said shift mechanism whenever a special character is sensed by said commutators.

26. In a typewriter controlled by a perforated record tape, said tape being divided into word representing areas, each area having three rows of index positions, wherein the letter representations are arranged for initial consonants, intermediate vowels, and final consonants in a left to right order, with error start and stop, capital start and stop, and special control indicia at the left of said letter representing indicia, and a space control index point at the right of said letter representing points, a set of type bars, solenoids for operating said type bars, two sets of sensing devices, each set comprising three rows of sensing brushes cooperating with the index points of successive areas, a pair of tape feeding means, one

for advancing the tape past the one sensing device and the other for advancing it past the other sensing device, a set of three commutators with segments connected individually to the sensing brushes at the second of the two sensing devices, means for operating said commutator devices to read the impulses from the brushes in a left to right order, means under control of said commutator devices for operating said solenoids, a carriage for holding the record sheet, means cooperating with the carriage for predetermining the length of the line of print, other means cooperating with said carriage to predetermine an area near the end of each line in which words are to be fitted, letter counting means, a set of commutator devices cooperating with the first set of sensing brushes for counting the number of letter perforations found under said brushes, means under

control of said last mentioned commutators for controlling operation of said counting means, carriage return mechanism, means under control of said counting means for selectively operating 5 said carriage return mechanism when words are too long, shift mechanism, means under control of the sensing devices cooperating with the capitalization perforations for initiating operation of said shift mechanism, print disabling controls, means for sensing said error start and error stop perforations, means under control of the last 10 mentioned sensing means for operating said print disabling means, escapement mechanism cooperating with the carriage, and means under control of said space perforation for operating said 15 escapement mechanism for word spacing.

WALDEMAR A. AYRES.
